UNITED STATES PATENT OFFICE.

SALVATORE DE BENEDICTIS, OF BROOKLYN, NEW YORK.

CIGAR-SHAPED PIPE.

Application filed August 26, 1925. Serial No. 52,523.

This invention has for its object a cigar-shaped pipe, and it is the principal object of the invention to provide a smoking pipe having the outer appearance of a cigar 5 cover, band, tip, and butt, perfectly simulating a cigar and perfectly hiding the pipe.

Another object of the invention is the provision of a cigar shaped smoking pipe, the joint between the pipe and its mouth piece 10 being entirely and completely hidden by the band of the cigar.

A further object of the invention is the provision of a cigar shaped pipe, the simulation of the cover leaf of which is adapted to 15 hide at its overlapping edges the air holes through which the necessary air is furnished to the smoking pipe.

A still further object of the invention is a cigar-shaped smoking pipe adapted to receive a cotton or the like nicotine absorbing 20 element making the smoking of a pipe sanitary and pleasant.

These and other objects and advantages of the invention will become more fully known 25 as the description thereof proceeds and will then be specifically pointed out in the appended claims.

In the accompanying drawing forming a material part of this disclosure:

30 Fig. 1 is a front elevation of a cigar-shaped smoking pipe constructed according to the present invention.

Fig. 2 is a view similar to Figure 1, with the tip and butt-end of the cigar separated 35 from its body part.

Fig. 3 is a longitudinal sectional view of the cigar-shaped smoking pipe showing the interior arrangement.

Fig. 4 is a section on line 4—4 of Figure 40 3.

Fig. 5 is an end view of the cigar shaped smoking pipe.

Fig. 6 illustrates in fragmentary detail 45 view a modified form of the butt-end.

A casing or body 10 having the shape of a cigar is covered by a simulation cover leaf 11 wound in the usual well known manner, in order to simulate a real tobacco cover leaf 50 with the overlapping seams 12. A removable tip 13 forms one end of the cigar while a removable butt-end 14 constitutes its opposite end.

Within the cigar shaped body the mouth piece 15 of the pipe is arranged having a 55 tapered outer end 16 and a channel or bore 17 and provided with threads at its lower

end adapted to receive the housing 18 having its upper end provided with inner threads adapted to engage the threads of the mouth piece. 60

The pipe bowl 19 is forced endwise into the housing 18 and has a neck part 20 formed therewith for the reception of a wad or cartridge 21 of absorbent material or the like. The housing 18 is provided with a plurality of air holes 22 for supplying the necessary draft air to the smoking pipe. The end of the pipe opposite to its mouth piece is constituted by a block 23 screwed into the end of housing 18 and adapted to be covered by the cap 14 which may be of leather or other suitable material not easily deteriorated by heat. The block or lug 23 has a plurality of radiating bores 24 formed therein, and its outer face is covered by a suitable material indicated at 25 to simulate the glow of a burning cigar. The modified form of end block 26 illustrated in Figure 6, is hinged at one end to the outer end of housing 27 of the pipe, and has also radiating channels 28, while its end opposite to the hinge 29 is shouldered as at 30 to snugly and frictionally engage the lower mouth of housing 27 as to be held in place therein. 70 75 80

The operation of my device will be entirely clear from the above description without further explanation, and it is to be understood, that such changes may be made in the construction disclosed herein as an example of the practical embodiment of my 90 invention as come within the scope of the claims without departure from the spirit of the invention. 85

Having thus described my invention, what I claim as new, and desire to secure by Letters Patent, is:

1. A cigar-shaped smoking pipe comprising an outer casing having an end closure on the rear end thereof and having a central aperture therein, an inner peripheral flange on the forward end of said casing, and a fire bowl comprising a rear tubular neck portion mounted in the aperture of said end closure, the forward end of said fire bowl being engaged by the inner flange of said casing, 100 said fire bowl being supported intermediate its ends in spaced relation to the inner walls of said casing. 105

2. A cigar shaped smoking pipe comprising an outer casing having an end closure on the rear end thereof and having a central aperture therein, an inner peripheral flange 110

on the forward end of said casing, a fire-bowl comprising a rear tubular neck portion mounted in the aperture of said end closure, the forward end of said fire bowl being engaged by the inner flange of said casing, said fire bowl being supported, intermediate its ends in spaced relation to the inner walls of said casing, a threaded boss on the outer end of the rear end closure of said casing, and a mouth piece comprising a central passage adapted to communicate with a passage in the neck portion of said fire bowl screw threaded on said threaded boss.

3. A cigar-shaped smoking pipe comprising an outer casing having an end closure on the rear end thereof and having a central aperture therein, an inner flange on

the forward end of said casing, threads on the forward portion of said flange terminating in advance of the rear end thereof, a fire bowl comprising a rear tubular stem portion mounted in the aperture of the rear end closure of said casing and a forward tubular portion supported at its forward extremity by said flange and being engaged by the inner walls of the rear portion of the latter, a threaded boss on the rear end closure of said casing, a mouth piece screw threaded on said boss, and a cap for the forward end of said casing screw threaded on the threads of said flange.

In testimony whereof I have affixed my signature.

SALVATORE DE BENEDICTIS.
